UNITED STATES PATENT OFFICE.

JOSEPH E. BOND, OF APPLETON, WISCONSIN.

AGITATOR.

Application filed March 5, 1928. Serial No. 259,085.

My invention relates to the art of paper making and particularly to means for agitating paper pulp.

In the development of the art it has been found possible to greatly increase the capacity of a given equipment by increasing the density (or, in other words, lessening the fluidity) of the pulp during its treatment preceding delivery to the Fourdriniers.

10 While in the old practice a 2½% pulp was considered proper and of the maximum density possible, it is now common to deal with 6% solutions, with correspondingly increased production capacity.

15 However, many difficult problems are encountered in handling pulp of this density due to its lack of fluidity and its tendency to mass or cake in the storage or treatment tanks and containers. This tendency is inherent in the nature of the material under treatment due to its fibrous character and to the physical law of attraction of solids. The liquid within which the solids are carried serves merely as a supporting medium 25 therefor and facilitates rather than hinders the massing and intertwining of the fibers.

To avoid massing and stratifying of the pulp in the liquid and to maintain a uniform density throughout the entire body of material it must be kept in motion and the motion producing means should have a tendency to break up and tear apart any large or small masses of pulp. In the old practice the mixture was kept in motion by means 35 of paddles or impellers in this tank, but this apparatus had very little tendency to break up masses of pulp, and was wholly ineffective with stock of increased density. Furthermore, such apparatus required an outlay 40 of power not commensurate with the results secured.

The tanks, chests or containers which are in place and must be utilized for the new plan of operation are of many and varied 45 forms, all of great size, some narrow and of great length, some deep and some round. The problem has been, therefore, to provide means applicable to these various forms of tanks that would insure effective circulation, 50 the breaking up of pulp masses and the maintenance at all times of a proper consistency throughout the whole volume of material, with a minimum of power expenditure.

55 My invention will be more readily under-

stood by reference to the accompanying drawing, in which—

Fig. 1 is a plan view of an agitator arranged in accordance with my invention, and

60 Fig. 2 is a longitudinal sectional view on the line 2—2 of Fig. 1.

In the drawings I have illustrated a substantially square tank of relatively great size and have provided means for adequate 65 agitation and circulation of liquid without the use of any internal baffles or division walls. The tank comprises side walls 10, 11 and end walls 12, 13. Three pumps 14, 15, 16 are positioned outside of the end 70 wall 13 and are operated by suitable motors. Each pump has a plurality of inlet pipes 17 communicating with the interior of the tank through the end wall at substantially the level of the floor. The material received 75 through these pipes passes through the screw pump and is discharged upwardly through the pipe 18 and thence horizontally through the pipe 19 to the far end of the tank where the pipe 19 terminates in a T, 20, and a 80 nozzle 21. Thus the entire body of material within the tank is agitated and kept in constant circulation by means of the pumps and the delivery pipes shown. This design is particularly applicable to large tanks in 85 which division walls are undesirable.

I claim:

1. In combination, a substantially square tank, a plurality of pumps each pump having a plurality of inlet connections with a 90 low level of said tank, and a discharge delivery pipe connected to each pump and extending horizontally within said tank to a point near the far end thereof.

2. In combination, a substantially square 95 tank, a plurality of pumps each pump having a plurality of inlet connections with a low level of said tank, and a discharge delivery pipe connected to each pump and extending horizontally within said tank to a 100 point near the far end thereof, and terminating in a plurality of differently directed outlets.

3. In combination, a substantially square tank, a plurality of pumps each pump having a plurality of inlet connections with a low level of said tank, and a discharge delivery pipe connected to each pump and extending horizontally within said tank to a 105 point near the far end thereof, said dis- 110

charge pipes terminating in a plurality of nozzles arranged to deliver material in opposite directions.

4. In combination, a chest, a plurality of pumps located exteriorly thereof, each pump having an inlet at substantially the level of the chest floor, a delivery pipe connected to the pump and extending longitudinally within the chest to a point near the far end of the chest, said pipe terminating in a plurality of oppositely directed outlets.
5. In testimony whereof I have affixed my signature.

JOSEPH E. BOND.
